Specification for Design.

Patented Nov. 2, 1920.

Application filed May 12, 1919. Serial No. 296,709. Term of patent 3½ years.

To all whom it may concern:

Be it known that I, MELVIN S. ACKLES, a citizen of the United States, residing at Fulton, in the county of Whiteside and State of Illinois, have invented a new, original, and ornamental Design for a Tire-Casing, of which the following is a specification, reference being had to the accompanying drawing, forming a part hereof.

Figure 1 is a plan view of a portion of a tire-casing, showing my new design, and Fig. 2 is a sectional view taken at the line 2—2 on Fig. 1.

I claim:

The ornamental design for a tire-casing, as shown.
